UNITED STATES PATENT OFFICE.

WILLIAM W. WARNER, OF CINCINNATI, OHIO.

STORM-SHIELD FOR VEHICLES.

SPECIFICATION forming part of Letters Patent No. 787,415, dated April 18, 1905.

Application filed December 8, 1904. Serial No. 235,973.

To all whom it may concern:

Be it known that I, WILLIAM W. WARNER, a citizen of the United States, residing at Cincinnati, in the county of Hamilton and State of Ohio, have invented certain new and useful Improvements in Storm-Shields for Buggies, of which the following is a specification.

The object of my invention is to provide a rain curtain or shield for carriage-tops which will be convenient, durable, and a complete protection to the occupants of the carriage against wind or rain.

The features of my invention are more fully set forth in the description of the accompanying drawings, forming a part of this specification, in which—

Figure 1 is a perspective view of my improvement applied to the bows of the carriage-top, the cover being omitted. Fig. 2 is an outside plan view of the entire curtain. Fig. 3 is an inside sectional plan view of the central tie-section. Fig. 4 is an inside plan view of the top fastening-section at one end. Fig. 5 is a section on line *ww*, Fig. 2. Fig. 6 is a detailed sectional view of the top section rolled.

A represents the front bow of the carriage.

B represents the vertical bow of the carriage adjacent to bow *A*, forming a part of a series of bows for supporting the cover and of ordinary construction well-known in the carriage trade.

C represents the body of the carriage.

D represents the dash.

35 The curtain is preferably made from a single piece of material, in which *a* represents the upper vertical shield portion, and *b* represents the lower or boot portion, provided with flaring skirts *c c'*, forming the side portion of the boot.

It is very desirable to have the upper top of the curtain durable and held in proper position, abutting the carriage-bow to make a complete shield. This is accomplished by the 45 following construction:

d represents a metal plate placed in a pocket formed between the face and the lining of the curtain and secured therein by a line of stitches *e e'*, duplicate construction being followed at 50 the opposite extremity of the shield *a*. To

these plates are firmly anchored elastic straps or cords *f*.

A slip-hem is formed along the top of the curtain, preferably by turning over the top end and hemming it down. The cords and 55 straps lie in this slip and are free to contract and expand.

g represents eyelet-holes punched through the curtain and end plates and engage hooks *h*, secured to the bows *B*, holding the top 60 portion of the curtain firmly against the front side of the bows *B*.

I represents a transparent light-section, preferably of celluloid, to allow the curtain to be rolled.

The boot portion *b* is provided with an aperture for the reins. This aperture is preferably covered by a flap *j*.

In order to adapt the curtain to different widths of carriages and to hold it tight to the 70 bows above the carriage-seat, I provide a slip or runway *k* and running across the curtain. In this slip is placed elastic cords or straps *l*, the ends of which are secured to the curtain.

m represents hooks firmly secured to the 75 end of the curtain, of size and shape to engage over the carriage-bows.

In order to fit the bottom of the boot to the dash, I provide a slip *n*, in which is placed elastic cord or straps *o*, to the ends of which 80 and to the curtain are firmly secured hooks *p*, adapted to engage the dash.

c c' represent the skirts of the boots, which fold down over the sides of the carriage-bottom.

The above storm-curtain is very neat, secure when in position, and perfect protection to the occupants of the carriage and when not in use can be readily rolled up and carried in any convenient position within the 90 body of the carriage. It can be readily attached in position for use.

The strap *p* (shown in Fig. 3) is intended to wrap around the curtain when rolled and hold the curtain in rolled position.

The method of constructing the hooks and elastic and uniting them together makes the fastenings very secure and durable.

The principal feature of the invention is illustrated in Fig. 4. For the top corner por- 100

tions of the vertical shield portion of the curtain I provide the metallic plates *d*. There is one plate for each corner. The outer edges of these plates correspond in contour to the curvature of the corner portions of the bow of the carriage-top. There is a ball-and-socket connection between the plates and the bow, and the plates are connected by the elastic tape *f*. These plates and the tape are secured between facings composing the said shield portion. By this means the shield portion makes a snug fit with the bow at the top of the carriage, which is always taut, and which is simple and durable.

Having described my invention, I claim—

1. In combination with a carriage top and bow, a storm-curtain having a vertical shield portion, a pair of metal plates secured to the top corner edges of said shield portion, said edges of shield and plates being curved to conform to the curvature of the carriage-top

bow, ball-and-socket connections between the said plates and the corner portions of said bow, and an elastic tape connecting the inner edges of said plates, substantially as described.

2. In combination with the carriage top and bow, a storm-curtain having a vertical shield portion comprising two facings, having secured between them a pair of metal plates, the outer edges of which are curved to conform to the curvature of the corner portions of the bow, an elastic tape uniting the inner edges of said plates between the facings, and ball-and-socket connections between the plates and bow, substantially as described.

In testimony whereof I have hereunto set my hand.

WILLIAM W. WARNER.
